UNITED STATES PATENT OFFICE.

JOHN DAWSON COX, OF PORTER, WASHINGTON.

NUT-LOCK.

1,180,572.

Specification of Letters Patent. Patented Apr. 25, 1916.

Application filed August 18, 1915. Serial No. 46,158.

To all whom it may concern:

Be it known that I, JOHN DAWSON Cox, a citizen of the United States, residing at Porter, in the county of Grays Harbor and 5 State of Washington, have invented certain new and useful Improvements in Nut-Locks, of which the following is a specification.

The present invention relates to a new and improved nut lock; and the main object 10 thereof is to provide a device of this character which is unusually simple in construction and which, it is believed may be manufactured at a minimum cost.

The invention contemplates the provision 15 of a nut lock wherein a substantially wedge shaped key is arranged in a vertically slotted bolt, the key carrying suitable radial projections which are engaged by the nut so that when the latter is moved into a secure 20 position, the key will be correspondingly actuated thus causing the bolt to expand and retain the nut against retrograde movement.

Various other objects and advantages will 25 become apparent during the continuance of the following description.

The above and other objects which will become apparent, are accomplished by such means as are shown in their preferred form 30 in the accompanying drawings, described in the following specification and then more specifically pointed out in the appended claims.

In the accompanying drawings wherein 35 like characters designate like parts throughout the several views, Figure 1 is a side elevation of my invention showing parts in section. Fig. 2 is a longitudinal sectional view of the device showing parts in elevation.

In the drawings the numeral 10 designates the shank of the bolt member which carries a head portion 11 at one end and is screw threaded a portion of its length adjacent the 45 other end as at 12. The screw threaded portion 12 is slotted as at 13, the slot 13 terminating in a somewhat restricted transverse cut out 14. The purpose of the cut out 14 is to add greater resiliency to the projecting ends of the screw threaded portion.

A wedge shaped key 15 is slidably arranged in the slot 13, the said key carrying a pair of outstanding projections 16. The 55 projections 16 extend beyond the periphery of the screw threaded portion of the bolt and operate in an annular cut out portion 17

in the nut 18. The function performed by the key 15 is thought to be readily obvious. As the nut 18 is rotated on the screw threaded portion of the bolt in a proper direction it will of course force the key along the slot 13. As the key is forced in the slot 13, the projecting ends of the screw threaded portion 12 will be uniformly spread so as to positively and effectually bind the nut in 65 place. In actual practice it has been found that the removal of the nut is positively prevented by the locking action that is attained.

The usual washer 19 is shown in the drawings in order to more properly set forth the 70 construction of my device.

From the foregoing it will be noted that this invention is exceedingly simple in construction and that the parts may be formed from stock material. In view of this construction the cheap cost of manufacture will 75 be readily recognized.

In reducing my invention to practice I find that the form referred to herein as the most practical and preferred embodiment is 80 the most efficient, but realizing that certain conditions will necessarily vary in concurrence with the adoption of my device, I desire to emphasize the fact that various minor changes in the details of construction and 85 in the proportion of parts may be resorted to when required without sacrificing any of the advantages of my invention as defined in the appended claims.

Having thus fully described my invention, what I claim as new and desire to secure by Letters Patent is:

1. In a nut lock, the combination with a bolt having a longitudinally extending slot formed therein, of a nut mounted to be movable on said bolt, a wedge key mounted to be slidable in said slot, said wedge key having its outer end terminating flush with the outer face of said nut, lateral projections on said wedge key, and said nut provided with a recess to receive said lateral projections, as and for the purpose specified.

2. In a nut lock, a bolt member, said bolt member being slotted a portion of its length, said bolt provided with a second slot of less 105 width than said first mentioned slot to communicate with said first mentioned slot, a nut member to be movably mounted on said bolt member, a wedge key to be slidable in said first mentioned slot, lateral projections 110 on said wedge member, said nut member provided with a recess to receive said lateral

projections, whereby said key may be moved positively in one direction in consistence with movement of the nut member, and said wedge key terminating flush with the inner and outer faces of the nut member whereby it will be protected at all times, as and for the purpose specified.

In testimony whereof I affix my signature in presence of two witnesses.

JOHN DAWSON COX.
